UNITED STATES PATENT OFFICE.

JACOB VOSBURGH, OF ST. LOUIS, MISSOURI, ASSIGNOR TO THE N. O. NELSON MANUFACTURING COMPANY, OF SAME PLACE.

FLOOR AND PARTITION THIMBLE.

SPECIFICATION forming part of Letters Patent No. 431,538, dated July 1, 1890.

Application filed November 4, 1889. Serial No. 329,237. (No model.)

To all whom it may concern:

Be it known that I, JACOB VOSBURGH, a citizen of the United States, and a resident of the city of St. Louis and State of Missouri, 5 have invented a new and useful Improvement in Floor and Partition Thimbles, of which the following is a specification.

My invention relates to thimbles such as are used to prevent injury to wood-work by 10 heat from steam-pipes passing through floors, ceilings, and partitions, and chiefly to that class of such thimbles which is adapted to be lengthened or shortened, so as to fit within certain limits, whether the partition, wall, or 15 the flooring, joists, and ceiling, as the case may be, are thick or thin.

The chief objects of my improvement are, first, to lessen the number of necessary parts; second, to make it possible to get an exact 20 fit, and, third, to so form the parts as to make it easy to put them in place and fasten them together with the least possible labor, and without making any opening in the floor or wall, except one just large enough to permit 25 of the thimbles being inserted.

Another object which I gain where the preferable form of my improved thimble is used is a more perfect protection from fire than is obtained where the old thimbles with which 30 I am acquainted are used.

I attain the objects above mentioned by the mechanism illustrated by the accompanying drawings, in which—

Figure 1 is a side elevation of my thimble 35 in its preferred form in place with the steam-pipe passing through it. Fig. 2 is a view showing the two parts of the thimble in elevation, but detached from each other. The packing is shown in section. Fig. 3 is a longitudinal section of the thimble, the parts being united. Fig. 4 is a bottom end view of the thimble.

Similar letters refer to similar parts throughout the several views.

40 The thimble is tubular and is formed in two parts—A and B. A is large enough at its inner end to receive the inner end of B.

a is a flange or collar.

a' is a covering of asbestos.

a² is a screw-thread on the inside of the 50 part A.

b is a screw-thread on the outside of the inner end of B, adapted to engage with the screw-thread *a²*.

b' is a flange or collar on the outer end of B. 55

b² is a covering of asbestos.

b³ b⁴ are screw-holes.

When the thimble is being screwed in place, the point of a hook-wrench may be inserted therein and greater ease in screwing the thimble up secured.

C is a steam-pipe.

In the drawings, A is the upper and B the lower part; but the positions of the parts may be reversed, if desired. 65

The flanges *a* and *b'* are preferably formed integral with the parts of the thimble to which they are respectively connected; but they may be formed out of separate pieces and attached to the thimble in any way desired, but preferably so as to turn with the connected part. The collars may, for instance, be formed with a hole in the center and slipped over the inner end of the parts to which they are to be attached, and the outer 75 end of such part may be so formed as to prevent the collars either turning or slipping off.

The thimble may be made of any fire-proof material. Where metal is used, I prefer to cover the necks of the thimble and the inner 80 sides of the flanges with a substance which is a poor conductor of heat—such as asbestos—as it insures a more perfect protection from fire; but such covering is not essential. The screw-thread should preferably extend 85 some distance out from the inner end of one of the parts, so as to permit of the thimbles being shortened by screwing the parts B into the part A for some distance, if desired.

The thimble need not be attached in place 90 by any outside fastening; but, if desired, screws may be passed through the holes *b³ b⁴* and into the ceiling *d'*.

The parts are put in place as follows: A hole is made through the floor and ceiling or 95 the partition-wall, as the case may be, through which the steam-pipe is to pass, and the small end of one part of the thimble is inserted

from one side and the small end of the other part from the other side, and the two parts are attached together by screwing the inner end of one part into the inner end of the other until the flanges are brought into close contact with the surfaces next thereto, as shown in Fig. 1. After the thimble is in place the steam-pipe C is passed through it. It is preferably a loose fit, so as to permit air to pass around it through the thimble, as well as for other purposes.

D, Fig. 1, represents a floor, in which the improved thimble is inserted.

d represents the upper side of the floor, and 15 d' the ceiling.

The part D may also represent a partition.

It should be particularly noted that the part or section A has instanding threads a^2 , and that the threaded and unthreaded parts 20 thereof are equal in diameter, and that the part or section B has outstanding threads b, and that the said threads b engage within the section A above the instanding threads a^2 , so that the lower section B can be lifted in 25 the section A without strain or breakage, the two sections thus yielding or giving in order to shorten or lengthen the thimble, so that it may accommodate itself to the jars or tremors of the parts of the floor or partition to which 30 it is attached, as the threads b can rise and fall in the spaces between the threads a^2 . This would be impossible with two sections having regularly-engaging screw-threads. Moreover, the upper section A, being of equal 35 diameter throughout, can be more snugly fitted into its opening in the floor D, and requires a smaller opening therein than if it had outstanding threads, and the smaller said opening is the better, as the upper section is 40 the supporting-section, which, if it had outstanding threads, must have its part thereabove enlarged in diameter. The lower section B has its lower end thus enlarged; but as

it supports nothing, but is itself supported by the upper section, this is immaterial; also, 45 as the threads b engage in the broad spaces between the threads a^2 (see Fig. 3) there is much less danger of binding than if the threads engaged in the ordinary manner. Thus the two sections close together or move 50 apart to accommodate the thimble to the fluctuations of the floor and ceiling therebelow or to two sections of a partition.

What I claim is—

1. A pipe-thimble composed of two parts 55 or sections, the upper and wider section being provided with instanding threads spaced a sufficient distance apart, and the lower and narrower section being provided with outstanding threads of less width than the 60 spaces between the thread of the upper section and arranged to engage internally between the threads of the upper section, substantially as specified.

2. A pipe-thimble composed of an upper 65 section of equal diameter throughout, provided with an outstanding circumferential flange at its upper end to rest on the floor when the section is inserted in an opening 70 therein and having instanding screw-threads spaced a suitable distance apart, and a lower section having an outstanding circumferential flange on its lower end and provided with outstanding screw-threads of less width than the 75 spaces between the threads of the upper section, the lower surfaces of which engage on the upper surfaces of the instanding threads of the upper section and permit the two sections to close in or open out, and thus automatically adjust the length of the thimble, substantially as specified.

Witness my hand this 31st of October, 1889.
JACOB VOSBURGH.
